DESIGN FOR A VEHICLE

Ernest T. Menard, Los Angeles, Calif.

Application January 30, 1940, Serial No. 89,886

Term of patent 3½ years

To all whom it may concern:

Be it known that I, Ernest T. Menard, a citizen of the United States and a resident of the city of Los Angeles, in the county of Los Angeles and State of California, have invented a new, original, and ornamental Design for a Vehicle, of which the following is a specification, reference being had to the accompanying drawing, forming part thereof.

In the drawing:

Fig. 1 is a side elevational view of a vehicle showing my new design.

Fig. 2 is a rear elevational view.

Fig. 3 shows a rear elevation of the forward section of my new design.

I claim:

The ornamental design for a vehicle, substantially as shown.

ERNEST T. MENARD.
